UNITED STATES PATENT OFFICE

100,782

DESIGN FOR AN AUXILERATOR AND MICROTELLING APPARATUS

Clinton H. Kibbe, New York, N. Y., assignor to Kibbe Auxilerator Corporation, a corporation of New York

Application May 9, 1936, Serial No. 62,562

Term of patent 14 years

To all whom it may concern:

Be it known, that I, Clinton H. Kibbe, a citizen of the United States residing at No. 87 Hamilton Place, New York city, in the county and State of New York, have invented a new, original, and ornamental Design for an Auxilerator and Micro-telling Apparatus, of which the following is a specification, reference being had to the accompanying drawing forming part thereof:

Fig. 1 is a perspective view of an Auxilerator and Microtelling apparatus showing my new design; and

Fig. 2 is a side elevation of the same.

I claim:

The ornamental design for an auxilerator and microtelling apparatus, substantially as shown.

CLINTON H. KIBBE.
